TOP ROLL UNIT FOR FIBER ATTENUATING APPARATUS

Earl W. Starnes, Alexander City, Ala., assignor to The Russell Manufacturing Company, Incorporated, a corporation of Alabama

Application January 24, 1955, Serial No. 483,665

13-Claims. (Cl. 19—131)

This invention relates to a top roll unit for fiber attenuating apparatus such as spinning frames, roving frames and the like and has for an object the provision of an alignment bracket connecting a needless front line top roll to a middle line top roll whereby alignment of the middle line top roll provides alignment for both middle and front line top rolls.

Another object of my invention is to provide an alignment bracket of the character designated which is adapted to support a top apron nose bar entirely independently of the middle line top roll, whereby there is no close contact of the nose bar or its apron guides with the middle line top rolls, thus eliminating complicated cradles heretofore employed on the middle line roll which have created choking and made the assembly very difficult to pick and clean.

A more specific object of my invention is to provide an alignment bracket of the character designated having a downwardly and rearwardly extending transverse slot adjacent the forward end thereof for receiving the shaft of a front line top roll intermediate the roll cylinders thereof, thereby to compensate for variation or irregularities in the diameters of the roll cylinders, such as occurs during normal wear of the cylinders or when the cylinders are buffed.

Another object of my invention is to provide an alignment bracket of the character designated which is adapted to support a holder for individual ton roll clearers.

Another object of my invention is to provide a top roll unit for fiber attenuating apparatus which can be checked for alignment and accuracy, including the front line top roll, prior to installation thereof and which can be installed and removed as a unit or the front line top roll can be removed and installed independently of the remainder of the unit.

A further object of my invention is to provide a top roll unit of the dual apron type which shall include removable spacer members adapted to support the top apron nose bar in spaced parallel relationship to the lower apron nose bar, whereby the spacer members can readily be removed and installed.

A still further object of my invention is to provide a top roll unit of the character designated which can readily be installed on conventional frames having lower line apron installations as well as on conventional frames converted to the lower line apron type and in which constant alignment of the rolls is maintained without adjustment and without the use of friction parts requiring lubrication, thus providing apparatus which produces a yarn of a constant and uniform quality.

As is well known in the art to which my invention relates, drafting apparatus having complicated cradles associated with the middle line top rolls are very difficult to pick and clean due to the close spacing of the stationary and moving parts over which the aprons must pass. Such close spacing causes an excess accumulation of lint due to the fact that lint accumulates where there is a

2

moving part adjacent a stationary part. Also friction and surface oils have created problems in the cleaning operation. Front line top rolls have heretofore been held in horizontal alignment by nebs at the ends thereof which fit in 90° slots in cap bars. This construction has been employed due to the fact that front line top rolls are not self-aligning, but must be rigidly held against horizontal movement. Also, difficulties have been encountered in supporting the top apron nose bar whereby it maintains spaced parallel relationship to the lower apron nose bar.

Briefly, my improved apparatus comprises an alignment bracket secured rigidly to the middle line top roll intermediate the roll cylinders thereof and extending forwardly thereof. A transverse slot is provided adjacent the forward end of the bracket for receiving the front line top roll intermediate the roll cylinders thereof whereby the front line top roll is maintained in parallel alignment with the middle line top roll and the bite of the upper and lower aprons, where such aprons are employed. A top line nose bar is secured rigidly to and supported by the alignment bracket a substantial distance forwardly of the middle line top roll around which the top aprons pass. The top apron nose bar is held in spaced parallel relation to the lower apron nose bar by means of removable spacer members which engage the ends of the nose bar outwardly of the apron guides. Also, supported by the alignment bracket is an upstanding holder for individual ton roll clearers.

30 Apparatus embodying features of my invention is illustrated in the accompanying drawing forming a part of this application, in which:

Fig. 1 is a plan view of the top roll unit, the holder for the top roll-clearers being cut away and in section for the sake of clarity.

35 Fig. 2 is a sectional view taken generally along the line III-III of Fig. 1.

Fig. 3 is an enlarged sectional view taken generally along the line III—III of Fig. 1.

40 Fig. 4 is a perspective view of the top roll unit removed from the frame and with the aprons, front line roll and clearer removed for the sake of clarity.

clearly removed for the sake of clarity;

Fig. 5 is a detail sectional view showing the upper and lower apron nose bars and the removable spacer member associated therewith.

45 Fig. 6 is a side elevational view, drawn to a smaller scale, showing the alignment bracket with a clearer holder thereon;

Fig. 7 is a sectional view showing a modified form of top roll unit in which individual removable lower line 50 nose bar sections are supported by and held in position

55 nose bar sections are supported by and held in position by the top apron nose bar; and

Fig. 8 is an exploded view showing the alignment bracket, the upper and lower apron nose bars, the holder for the top roll clearer and the means for securing the elements together.

Referring now to the drawings for a better understand-

60 Referring now to the drawings for a better understanding of my invention I show my improved alignment bracket at 10 which is provided with a downwardly opening slot 11 adjacent the rear end thereof and an upwardly opening slot 12 adjacent the forward end thereof. The upwardly opening slot 12 extends downwardly and inwardly as shown in Figs. 3, 4 and 6, for a purpose to be described more in detail hereinafter. Extending transversely 65 of the alignment bracket 10 and positioned within the slots 11 and 12 are shafts 13 and 14 of middle and front line top rolls 16 and 17, respectively. Mounted on the shaft 13 at opposite sides of the bracket 10 are roll cylinders 18 having knurled surfaces, as shown in Figs. 2 and 4. The roll cylinders 18 are supported on the shaft 13 by 70 suitable roller bearings 19. Mounted for rotation on the shaft 14 on opposite sides of the bracket 10 are roll cylinders

ders 21. Suitable roller bearings 22 are interposed between the roll cylinders 21 and the shaft 14, as shown in Fig. 2.

A transverse slot 23 is provided in the undersurface of the bracket 10 intermediate the slot 11 and 12 for receiving a top apron nose bar 24. Secured to the under surface of the bracket 10 by means of a cap screw 26 is a longitudinally extending clamp member 27. As shown in Figs. 2 and 3, the clamp member 27 extends across the downwardly opening slot 11 and across a portion of the slot 23, thereby securing the shaft 13 and the nose bar 24 rigidly to the bracket 10. As shown in Fig. 1, the ends of the shaft 13 are held in alignment by slots 28 provided in cap bars 29.

Passing over the roll cylinders 18 and the nose bar 24 are continuous aprons 31 formed of a suitable material, such as leather, rubber or synthetic materials. Secured to the nose bar 24 by any suitable means such as by welding or riveting, are apron guides 32 which hold the aprons 31 in alignment in a manner well understood. As shown in Figs. 1, 2 and 4, the nose bar 24 and the apron guides 32 do not contact any part of the shaft 13 or the roll cylinders 18 of the middle line top roll. The nose bar 24 is centered relative to the bracket 10 by providing a depression or opening 33 in the nose bar for receiving a projection 34 on the upper surface of the clamp member 27. The shaft 13 is centered relative to the bracket 10 by providing an annular groove 35 at the center thereof for receiving the upper surface of the clamp member 27, as shown in Fig. 3.

As shown in Figs. 2 and 3, the upper apron 31 engages a lower apron 36 which passes over a lower apron nose bar 37 and a bottom middle roll 38. The front line top roll 17 engages a lower line front roll 39. The front line and middle line top rolls are weighted against the driven lower line roll 39 and the lower apron 36 by saddles 41 and 42 and weight hooks 43.

The top roll unit is held in parallel spaced alignment with the lower line nose bar 37 and the travel of the apron 36 thereover by means of removable spacer members 44. The spacer members 44 are installed at the extreme ends of the top apron nose bar 24, as shown in Figs. 4 and 5, and are in the form of snap-on clips which partially surround the ends of the nose bar. Depressions 46 are provided in the nose bar 24 adjacent the ends thereof in position to receive inwardly extending projections 47 on the spacer members 44. Formed integrally with the portion of the spacer member 44 which surrounds the nose bar 24 is a downwardly and then forwardly extending flange 48. As shown in Fig. 5, the lower surface of the flange 48 extends in a direction substantially parallel to the upper surface of the lower nose bar 37. Due to the fact that the snap-on spacer members 44 may be easily installed and removed from the nose bar 24, different size spacer members may be employed for different size yarn and may be exchanged without removing the top roll unit or any part thereof from its normal position in the frame.

Formed integrally with the bracket 10 is an upstanding holder 49 having upwardly opening slots 50 therein for supporting individual top roll clearers 51 which turn with the front line top roll 17. While I show the holder 49 for the front line top roll clearers as being formed integrally with the bracket 10, it may be formed as a separate part and attached to the bracket 10 by any suitable means. Also, the clearers 51 may be in the form of continuous clearers for use on a plurality of sets of front line top rolls. For such a continuous clearer, the slots in the holders 49 would be wider to accommodate the same.

To compensate for irregularities in the diameters of the front line top roll cylinders, such as occur when the cylinders are buffed or worn, the upwardly opening slot 12 extends downwardly and inwardly, as shown in Figs. 3, 4 and 6, whereby as the diameter of the roll cylinders

21 decreases the shaft 14 moves toward the bottom of slot 12. This construction maintains a constant distance between the point of contact of the rolls 21 and 39 and the bite of the aprons 31 and 36. Also, a constant distance is maintained between the point of contact of the rolls 21 and 39 and the middle line top roll 16. The location of the front line top roll 17 forward of the front line bottom roll 39 together with the rotation of the rolls and the downward weighting causes the roll shaft 14 always to rest with pressure against the forward side of the slot 12 in bracket 10. Accordingly, the forward side of the slot 12 is cut an angle whereby the variations in the diameters of the roll cylinders is compensated for and a constant distance is maintained between the point of contact of the front line rolls and the bite of the aprons regardless of how the cylinders wear or are buffed.

From the foregoing description it will be seen that the front line top roll 17, the middle line top roll 16, and the top apron nose bar 24 and the aprons 31 which pass over the middle line top rolls and the top apron nose bar form an assembly, all parts of which may be checked for accuracy and alignment prior to installation and then installed on the frame as a unit. To remove the top roll unit from the frame, the weighting is merely lifted, thus permitting the entire unit to be removed. Also, the front line top roll may be removed independently of the remainder of the assembly.

In Figs. 7 and 8 I show a modified form of top roll unit comprising an alignment bracket 10a having a downwardly opening slot 11a adjacent the rear end thereof for receiving the middle line top roll shaft 13a, having roll cylinders 18a mounted thereon. A transverse slot 23a is provided in the bracket 10a for receiving a top apron nose bar 24a. The shaft 13a and the nose bar 24a are secured rigidly to the bracket 10a by means of a clamp member 27a and a cap screw 26a.

In the construction shown in Figs. 7 and 8 the lower apron nose bars are supported by the top apron nose bar and are removable therefrom. Inner guide members 54 are mounted on the upper surface of the top apron nose bar indicated at 52 and secured to the undersurface of the nose bar 52 are inner apron guides 53 for the lower aprons 36a. The lower apron nose bar is in the form of sections 56 which are attached to outer apron guide members 57, as shown in Fig. 8. The outer ends of the top apron nose bar 52 are reduced as at 58 and the reduced portions extend outwardly and thence forwardly to provide hooks 59 which engage openings 61 in the outer apron guide members 57, thus removably attaching the outer ends of the upper apron nose bar 52 to the lower apron nose bar sections 56. The inner guides 53 are provided with forwardly opening slots 62 therein for receiving the inner ends of the lower apron nose bar section 56, thus limiting rearward movement of the inner ends thereof. There is no forward movement of the lower apron nose bar sections 56 due to the fact that the apron 36a passes around the same and the lower middle line roll 38a, as shown in Fig. 7.

The holder 49a for the individual top roll clearers is formed separately from the bracket 10a and is attached thereto by any suitable means, such as rivets 55. A downwardly opening slot 12a is provided adjacent the forward end of the bracket 10a for receiving the shaft 14a of the front line top roll.

From the foregoing it will be seen that I have devised an improved top roll unit for fiber attenuating apparatus. By providing an alignment bracket which connects and aligns the front line top roll with the middle line top roll, the front line top roll is aligned without the necessity of nebs at the ends thereof. Also, the front line top roll maintains its alignment with the middle line top roll although variations or irregularities occur in the diameters of the roll cylinders. By supporting the top apron nose bar from the alignment bracket independently of the

middle line top roll, there is no close contact of the nose bar, or its apron guides with the middle line top rolls. Furthermore, by maintaining spaced parallel relationship between the top and lower apron nose bars by means of the removable spacer members at the ends thereof, the spacer members can be removed and installed without the removal of the top roll unit from the frame. In actual practice, I have found that my improved top roll unit is satisfactory in every respect and constant alignment of the rolls and the aprons is maintained at all times without adjustments.

While I have shown my invention in but two forms, it will be obvious to those skilled in the art that it is not so limited but is susceptible of various other changes and modifications without departing from the spirit thereof, and I desire, therefore, that only such limitations shall be placed thereupon as are specifically set forth in the appended claims.

What I claim is:

1. The combination with a top roll unit for fiber attenuating apparatus including middle and front line top rolls having shafts with spaced roll cylinders mounted thereon, the ends of the shaft of the middle line top roll projecting outwardly of the roll cylinders and means engaging the outwardly projecting ends of the middle line top roll and holding the middle line top roll in predetermined alignment, of a bracket secured rigidly to the middle line top roll intermediate its roll cylinders and extending forwardly thereof, there being a transverse slot adjacent the forward end of said bracket receiving said front line top roll intermediate its roll cylinders and holding said front line top roll in parallel alignments with the middle line top roll, whereby said front line top roll is aligned entirely by said bracket and the bracket connection to the middle line top roll.

2. In a top roll unit for apron type fiber attenuating apparatus including front and middle line top rolls having shafts with spaced roll cylinders mounted thereon, a bracket secured rigidly to the middle line top roll intermediate its roll cylinders and extending forwardly thereof, a top apron nose bar secured rigidly to said bracket forwardly of said middle line top roll, and aprons passing around the roll cylinders of the middle line top roll and said nose bar, there being a transverse slot adjacent the forward end of said bracket disposed to receive said front line top roll intermediate its roll cylinders and hold said front line top roll in parallel alignment with the middle line top roll.

3. In a top roll unit for apron type fiber attenuating apparatus including front and middle line top rolls having shafts with spaced roll cylinders mounted thereon, an alignment bracket, there being a downwardly opening transverse slot adjacent the rear end of said bracket disposed to receive a part of the middle line top roll intermediate its roll cylinders, there being an upwardly opening transverse slot adjacent the forward end of said bracket disposed to receive a part of the front line top roll intermediate its roll cylinders, there being a third transverse slot in said bracket forwardly of said downwardly opening slot, a top apron nose bar fitting within said third transverse slot, aprons passing around the roll cylinders of the middle line top roll and said nose bar, a clamp member spanning at least a portion of said nose bar and said part of the middle line top roll, and means securing said clamp member to said bracket.

4. A top roll unit as defined in claim 3 in which the nose bar is provided with a recess adjacent the center thereof for receiving an upstanding projection on the clamp member, whereby the nose bar is centered relative to the alignment bracket.

5. The combination with a top roll unit for fiber attenuating apparatus including middle and front line top rolls having shafts with spaced roll cylinders mounted thereon, the ends of the shaft of the middle line top roll projecting outwardly of the roll cylinders and means

engaging the outwardly projecting ends of the middle line top roll and holding the middle line top roll in predetermined alignment, of an elongated bracket having a downwardly opening transverse slot adjacent the rear end thereof receiving the shaft of said middle line top roll intermediate its roll cylinders, means operatively connecting the shaft of said middle line top roll to said bracket and limiting fore and aft movement of said middle line top roll relative to said bracket, there being an upwardly opening transverse slot adjacent the forward end of said bracket receiving the shaft of said front line top roll intermediate its roll cylinders and holding said front line top roll in parallel alignment with the middle line top roll, whereby said front line top roll is aligned entirely by said bracket and the bracket connection to the middle line top roll.

6. Apparatus as defined in claim 5 in which the sides of the upwardly opening slot adjacent the forward end of the bracket extend downwardly and inwardly where-
20 by the distance between the bites of the front line rolls and middle line rolls remains substantially constant when the diameters of the front line top rolls are varied.

7. In a top roll unit for dual apron type fiber attenuating apparatus including front and middle line top rolls having shafts with spaced roll cylinders mounted thereon, a bracket secured rigidly to a stationary part of the middle line top roll intermediate its roll cylinders and extending forwardly thereof, a top apron nose bar secured rigidly to said bracket forwardly of said middle line top roll, top aprons passing around the roll cylinders of the middle line top roll and said nose bar, there being a transverse slot adjacent the forward end of said bracket disposed to receive said front line top roll intermediate its roll cylinders and hold said front line top roll in parallel alignment with the middle line top roll, and removable spacer members mounted adjacent each end of said top apron nose bar and disposed to support the same in parallel spaced relation to a subjacent nose bar.

8. In a top roll unit for dual apron type fiber attenuating apparatus including front and middle line top rolls, a bracket secured rigidly to said middle line top roll and extending forwardly thereof, means adjacent the forward end of said bracket supporting the front line top roll in parallel alignment with the middle line top roll, a top apron nose bar secured rigidly to said bracket forwardly of the middle line top roll, and removable spacer members mounted adjacent the ends of said top apron nose bar disposed to support the top apron nose bar in parallel spaced relation to a subjacent nose bar.

9. A top roll unit as defined in claim 8 in which the spacer members are in the form of snap-on clips disposed to encircle a portion of the top apron nose bar.

10. A top roll unit as defined in claim 9 in which the ends of the top apron nose bar are provided with depressions for receiving inwardly extending projections on the snap-on clips, and the snap-on clips have flanges along the lower portions thereof which extend downwardly and then outwardly.

11. In a top roll unit for dual apron type fiber attenuating apparatus including front and middle line top rolls, a bracket secured rigidly to said middle line top roll and extending forwardly thereof, a transverse slot adjacent the forward end of said bracket supporting the front line top roll intermediate its roll cylinders, a top apron nose bar secured rigidly to said bracket a substantial distance forwardly of the middle line top roll, and means attaching lower apron nose bar sections to said top apron nose bar.

12. A top roll unit as defined in claim 11 in which inner 70 apron guides are mounted on the upper and lower surface of the top apron nose bar, and outer apron guides are attached to the lower apron nose bar sections, there being slots in the inner apron guides mounted on the lower surface of the top apron nose bar for receiving the inner 75 ends of said lower apron nose bar sections, and there

being slots in the outer apron guides for receiving the outer ends of said top apron nose bar.

13. A top roll unit as defined in claim 12 in which the top apron nose bar is provided with hook portions at the ends thereof disposed to engage the slots in the outer 5 apron guides.
